US00D872127S

(12) **United States Design Patent** (10) Patent No.: **US D872,127 S**
Alonso Ruiz et al. (45) Date of Patent: **** Jan. 7, 2020**

(54) **DISPLAY SCREEN OR PORTION THEREOF WITH ANIMATED GRAPHICAL USER INTERFACE**

(71) Applicant: **Apple Inc.**, Cupertino, CA (US)

(72) Inventors: **Marcos Alonso Ruiz**, San Francisco, CA (US); **Patrick Lee Coffman**, San Francisco, CA (US); **Richard Dellinger**, San Jose, CA (US); **Stephen O. Lemay**, Palo Alto, CA (US); **Brandon Walkin**, San Francisco, CA (US)

(73) Assignee: **Apple Inc.**, Cupertino, CA (US)

(**) Term: **15 Years**

(21) Appl. No.: **29/656,703**

(22) Filed: **Jul. 16, 2018**

Related U.S. Application Data

(63) Continuation of application No. 29/606,423, filed on Jun. 5, 2017, now Pat. No. Des. 823,338.

CLAIM

The ornamental design for a display screen or portion thereof with animated graphical user interface, as shown and described.

DESCRIPTION

FIG. 1 is a front view of a display screen or portion thereof with animated graphical user interface showing the claimed design;

FIG. 2 is a second image thereof;

FIG. 3 is a third image thereof;

FIG. 4 is a fourth image thereof;

FIG. 5 is a fifth image thereof; and,

FIG. 6 is a sixth image thereof.

The outermost broken lines in the figures show a display screen or portion thereof, and form no part of the claimed design. The other broken lines in the figures show portions of the animated graphical user interface that form no part of the claimed design.

1 Claim, 6 Drawing Sheets
